UNITED STATES PATENT OFFICE

143,764

DESIGN FOR A SALT SHAKER OR SIMILAR ARTICLE

Egbert Smith, Fort Myers, Fla.

Application August 2, 1945, Serial No. 121,160

Term of patent 3½ years

(CL. D44—22)

To all whom it may concern:

Be it known that I, Egbert Smith, a citizen of the United States of America, residing in Fort Myers, county of Lee, and State of Florida, have invented a new, original, and ornamental Design for a Salt Shaker or Similar Article, of which the following is a specification, reference being had to the accompanying drawing, forming part thereof.

Fig. 1 is a front view of a salt shaker or similar article showing my new design.

Fig. 2 is a rear view thereof.

Fig. 3 is a side view.

The dominant feature of my design resides in the portions shown in solid lines.

I claim:

The ornamental design for a salt shaker or similar article, substantially as shown and described.

EGBERT SMITH.
